CLAIM

The ornamental design for a bathroom hardware support, as shown and described.

DESCRIPTION

FIG. 1 is a perspective view of a bathroom hardware support showing our design;

FIG. 2 is an alternate perspective view;

FIG. 3 is an alternate perspective view; and,

FIG. 4 is an alternate perspective view.

The broken-line disclosure in the views represents portions of the bathroom hardware support in which the claimed design is embodied, but which form no part of the claimed design.

1 Claim, 4 Drawing Sheets

FIG. 3
